(57) **CLAIM**

I claim the ornamental design for an air hose nozzle for dental mirror, as shown and described.

DESCRIPTION

FIG. 1 is a front perspective view of an air hose nozzle for dental mirror showing our design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof showing environmental elements that form no part of the claimed design. The broken lines shown in the figures show environmental elements for the air hose nozzle for dental mirror that form no part of the claimed design.
